ICE PACK

Joseph D. Bates, Springfield, Mass.

Application June 15, 1936, Serial No. 85,425

5 Claims. (Cl. 150—2.1)

This invention relates to devices which are intended to be applied to a part of the human body or to any article to cool the same by removing heat therefrom.

5 By the present invention it is proposed to provide a hollow impervious receptacle or container having a substantial quantity of a liquid sealed therein, which container may be placed in a refrigerator or other cooling device to freeze the 10 entrapped liquid. This device may then be applied to the body part, or article to be cooled, and being relatively colder than the part or article to be cooled, will remove heat therefrom and cool and maintain cold the part or article to which 15 it is applied. While devices of this general type have been heretofore proposed, the novel construction of the container according to the present invention provides considerable advantages over prior art constructions.

20 It is an object of this invention to provide a cooling appliance of the type described which will be so constructed as to permit it, when the entrapped liquid is frozen, to be bent to conform to any part or article which it is desired to cool and 25 to which the cooling device may be applied.

Another object is to provide a cooling device of the type described which will be provided interiorly with means about which the ice will be frozen and which, when the device is bent to 30 adapt it to a body part or article to be cooled, will cause the ice to be broken into small and relatively uniform pieces which will be so disposed within the device as not to present any 35 bumps or protruding edges.

35 It is also an object of the invention to provide a cooling appliance of the type described which may be easily and cheaply manufactured and which will be strong and rugged in construction.

Other objects and features of novelty will be 40 apparent from the following description and the annexed drawing, it being clearly understood, however, that the invention is not limited in any way by such description and drawing, which are illustrative only, or otherwise than by the 45 appended claims.

Referring to the drawing, in which similar reference numerals refer to like parts,

Fig. 1 is a perspective view of a cooling appliance which may be formed according to the 50 present invention;

Fig. 2 is a cross sectional view taken on the line 2—2 of Fig. 1 and showing one form which the invention may take;

Fig. 3 is a view, similar to Fig. 2, and showing 55 a modified form of the invention;

Fig. 4 is a view taken on the line 4—4 of Fig. 3, and

Fig. 5 is a view taken on the line 5—5 of Fig. 1 and showing a further form which the invention may take.

According to this invention, I propose to provide a sealed container which is preferably formed of flexible, impervious material, preferably rubber, and in which is sealed a quantity of a liquid, such as water, which may be frozen in such an 10 ordinarily-available cooling device as a household refrigerator by placing the entire device within the refrigerator. Such a cooling appliance is illustrated generally in Fig. 1 and it will be seen that the same may be formed, if desired, 15 of two substantially flat open-sided receptacle members 1, 2 disposed in face-to-face engagement and united by vulcanizing or otherwise attaching their meeting edges. As illustrated in Fig. 1 these members may have formed, about the free 20 edges thereof, flanges 3, 4 which abut when the two members are brought together and which may be united in the manner described to thereby provide a hollow container which is formed of impervious, preferably flexible material. A quantity of a liquid, preferably water, 25 is put into this container before the sealing operation, this quantity of water being preferably less than the volume of the container in order to prevent any possible rupture of the container 30 when the included liquid is frozen. It will be apparent that the method of inserting the liquid into the appliance forms no part of the invention, and the liquid may, if desired, be injected 35 into the container after the sealing operation has been performed. It has been found that the best results are obtained by removing a substantial part of the air from the container before sealing the same, as the presence of a substantial amount of air within the container retards the freezing 40 of the water therein.

One form which my invention may take is illustrated in Fig. 2 and, referring to this figure, it will be seen that means are provided for preventing the formation of a solid mass or sheet 45 of ice within the receptacle. Such means comprise, in this form of the invention, a plurality of posts or studs 5, which are preferably formed integrally with and of the same material as one of the outer walls of the receptacle, and which 50 extend from such wall toward the opposite wall and into the interior of the container. These posts or studs may be of any desired thickness or shape and, in this form of the invention, are of such a length that they extend approximately to 55

the opposite wall of the container and may be regularly or irregularly spaced on the wall from which they extend. It is preferred that the posts or studs be spaced over substantially the entire area of the container so that no considerable portion of the area thereof will be without such posts or studs.

In the form of the invention illustrated in Fig. 3 each of the wall members 1, 2 is provided with studs or posts 6, 7, the studs carried by one wall, extending toward the studs carried by the other wall. These studs are preferably formed of such length that they do not overlap each other, although they may, if desired, be of such length that they overlap and extend from one face or wall into the other half or portion of the container. If the studs are so formed that they do not overlap each other, as illustrated in Fig. 3, the studs extending from opposite wall members 20 may be disposed opposite each other or may be staggered with relation to each other.

Regardless of the length or disposition of the studs, it will be seen that they will extend into the liquid entrapped within the container and, when such liquid is frozen, will, in effect, form holes in the ice and prevent the formation of a solid mass or sheet of ice within the appliance thereby permitting the ice to be broken into small, regular pieces. In the preferred form of 30 the invention the studs are arranged over the entire area of the cooling appliance, and consequently the ice which is formed therein is formed in only small connected masses which are easily broken apart. The entire appliance may, therefore, be easily bent with the hands to any desired shape and after being bent, the ice therein will be in small regular pieces instead of being in large, free, irregular lumps as in the usual ice pack.

40 In the embodiment of my invention disclosed in Fig. 5, the cooling appliance may take the same form and be constructed in the same manner as that disclosed in Fig. 1. In this modification, however, the studs are omitted and the hollow interior of the appliance is filled, or substantially filled, with a sponge rubber element, or a plurality of smaller similar elements. This sponge rubber member is saturated with a liquid, such as water, preferably before being sealed within 45 the appliance. When required, the cooling appliance so formed may be placed within a refrigerator or other cooling device and the entrapped liquid frozen. It will be apparent that the ice which will be formed within the appliance will be completely enmeshed with the sponge rubber. This will effectually prevent the formation of any large rigid mass of ice and will insure that the ice formed within the appliance may be easily broken, whereby the cooling appliance 50 may be easily and quickly bent to any desired shape.

It will be apparent that the appliance, instead of being formed of two connected members, may be formed in any other manner and in any desired shape. Also, if desired, the two halves of the container may be connected in some manner whereby they may be separated, either wholly or partly. If such a construction is employed, the container need only be filled with liquid when it 65 is to be used and at other times the liquid may be removed therefrom. The appliance may also be formed of any material other than rubber, as desired.

While it is primarily intended that the appliance hereinbefore described be employed as a

cooling device, it will be apparent that it may be used as a heating pad by applying heat thereto instead of cooling the appliance. Also, while the device described is particularly adapted for therapeutic uses, it will be apparent that it may be employed whenever it is desired to cool any article, foodstuff or other material, and while certain of the claims may refer to the invention as a therapeutic device it will be understood that this term is descriptive only and is not to be construed as placing any limitation on the scope of the claims.

It may be found to be desirable to form the container of the invention as a single unitary bag. In this event the posts cannot easily be formed on the inner surfaces of the walls of the bag and, with such a construction, my invention contemplates that a flat partition member having posts or studs over substantially the entire area of both sides thereof be formed and be inserted within the bag to thereby divide the bag into two flat portions each having studs or posts extending therein. If desired, this studded partition sheet may be formed of thin, bendable sheet metal, as may be all portions of the present invention.

While in the preferred form of the invention the studs form the means for insuring that the ice within the container may be easily broken, it is also proposed that instead of the posts or studs, the opposite inner walls of the container be provided with laterally-extending ridges or alternate ridges and grooves, whereby the ice is frozen into alternate thick and thin portions and may be easily broken. Such ridges may be formed on the opposite sides of the partition sheet described above, in place of the studs thereon.

While I have illustrated and described various forms of my invention, it will be apparent to those skilled in the art that the invention is susceptible of other forms and modifications, and that improvements may be made therein, all without departing in any way from the spirit or scope of the invention, for the limits of which reference must be had to the appended claims.

What is claimed is:

1. A therapeutical device, comprising a container adapted to contain a liquid, and a sponge rubber member disposed within said container and lying within the liquid within said container and adapted to prevent the formation of large masses of ice within said container when said liquid is frozen, whereby said device may be easily bent to a desired shape.

2. A therapeutical device comprising a hollow container formed of flexible material and having a quantity of a liquid contained therein, and a member disposed within said container and comprising a flexible mass which substantially fills the space within said container and which is formed with a large number of openings throughout which communicate with the exterior of said member and within which the liquid within said container is received, said member being adapted to prevent the formation of large masses of ice within the container when the liquid therein is frozen, whereby the device may be bent to a desired shape.

3. A therapeutical device comprising a hollow container formed of flexible material and having a quantity of a liquid sealed therein, and a separate member disposed within said container and comprising a flexible perforate mass which substantially fills the space within said container and which is formed with a large number of

openings throughout which communicate with the exterior of said member and within which the liquid within said container is received, said member being adapted to prevent the formation of 5 large masses of ice within the container when the liquid therein is frozen, whereby the device may be bent to a desired shape.

4. A therapeutical device comprising a hollow, closed container formed of flexible material and 10 having a quantity of a liquid contained therein, and a plurality of perforate members disposed within said container and which substantially fill the space within said container, each of said members being formed with a large number of

openings throughout which communicate with the exterior thereof and within which the liquid within said container is received, whereby the liquid within said container, when frozen, will form small, irregular masses of ice which may be 5 easily broken to permit the device to be bent to a desired shape.

5. A therapeutical device comprising a hollow, closed container formed of flexible material, and 10 a fluid-saturated sponge-like member disposed within and substantially filling the space within said container, the fluid within said member being adapted to be frozen.

JOSEPH D. BATES.
